CLAIM

The ornamental design for a hard disk drive, as shown and described.

DESCRIPTION

FIG. 1 is a top perspective view of a hard disk drive according to a first embodiment showing my new design; FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1;

FIG. 10 is a top perspective view of a hard disk drive according to a second embodiment;

FIG. 11 is a bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is a partial enlarged view taken from circle 18 in FIG. 10.

The dash-dash broken lines in the drawings depict the portions of the hard disk drive which form no part of the claimed design.

The dot-dash broken lines depict the boundary of partial enlarged views and form no part of the claimed design.

1 Claim, 18 Drawing Sheets
